United States Patent Office

Des. 217,880
Patented June 23, 1970

217,880

LINK FOR AN IDENTIFICATION BRACELET OR SIMILAR ARTICLE

Murray L. Cowan, Norwood, Mass., assignor to Textron
Inc., Providence R.I., a corporation of Delaware

Filed July 16, 1969, Ser. No. 18,229

Term of patent 14 years

Int. Cl. D11—01

U.S. Cl. D45—4

FIG. 1

FIG. 3

FIG. 1 is an enlarged top plan view of a link for an identification bracelet or similar article, showing my new design;

FIG. 2 is a reduced side elevational view thereof; and
FIG. 3 is a reduced end elevational view thereof.

The side opposite that shown in FIG. 1 is substantially plain and unornamental.

I claim:

The ornamental design for a link for an identification bracelet or similar article, substantially as shown and described.
